UNITED STATES PATENT OFFICE.

OLAUS C. WOLD, OF CHICAGO, ILLINOIS.

AIR-BRUSH.

1,017,358.

Specification of Letters Patent. Patented Feb. 13, 1912.

Application filed May 5, 1911. Serial No. 625,356.

To all whom it may concern:

Be it known that I, OLAUS C. WOLD, a citizen of the United States, residing at Chicago, in the county of Cook and State of Illinois, have invented certain new and useful Improvements in Air-Brushes, of which the following is a specification.

This invention relates to air brushes of the general type shown and described in Letters Patent of the United States No. 767,510, and No. 910,341, issued to me on the 16th of August, 1904, and the 19th of January, 1909, respectively. In the form of air brush disclosed in the first mentioned patent, namely, No. 767,510, the air is delivered through an annular opening which completely surrounds the opening through which the color is delivered, while in the second mentioned patent, namely, No. 910,341, the air is delivered through a single orifice, located beneath that through which the coloring matter is discharged. The air brushes of both of said patents tend to discharge the coloring matter in a somewhat irregular manner, so that it is not delivered onto the paper in the form of a thin, flat line, as is the case when using a fine hair brush of ordinary form.

The main object of the present invention is to provide an air brush which will deliver the color in the form of a spray, resembling as much as possible the effect which is produced in drawing a line with a fine hair brush. To this end, I provide means for delivering a fine jet of air on each side of the color orifice, the result being that the color is delivered in the form of a very fine flat jet.

Other objects are to generally improve the discharge end of the air brush, and to construct it in such manner that the air chamber and discharge pipes will be easily accessible for the purposes of cleaning or repair without in any way disturbing the needle valve and associated parts which control the flow of color. Also to provide an air discharge member of such form that it may be easily removed and replaced by one having larger openings, and adapted to deliver larger jets of air for rougher or heavier work.

Other objects and uses will appear from a detailed description of the invention which consists in the features of construction and combination of parts hereinafter described and claimed.

Referring now to the drawing, Figure 1 shows a plan view of the brush; Fig. 2 shows a detailed cross section of the forward portion of the brush taken on the line 2—2 of Fig. 1, looking in the direction of the arrows; Fig. 3 shows a plan detail taken on the line 3—3 of Fig. 2, looking in the direction of the arrows; Fig. 4 shows a detail of the color receptacle taken on the line 4—4 of Fig. 3 looking in the direction of the arrows; and Fig. 5 shows a greatly enlarged plan detail cross section of the discharge tip of the air pipes and the needle valve.

Referring now to the drawings, the air is delivered to the air brush through a valve 6, the opening and closing of which are controlled by the vertical movements of a button 7. A spring 8 normally keeps the valve closed. The air passes up through passages 9 and 10 into a chamber 11 in the forward end of the brush. The color is carried in a pan 12, the siphon connection 13 of which is swivel-jointed to the body of the air brush at 14, the color thence passing into a chamber 15. A needle rod 16 extends through the color chamber 15, its backward and forward movements being controlled by the back and forth movements of the button 7, a spring 17 normally throwing the needle rod forward to close the needle valve.

The elements which I have thus far described are not new in this present application, and their description is only necessary in order to show the general manner in which my present air brush is constructed.

I will now describe the forward portion of the brush including the needle valve for controlling the flow of color and the air discharge pipes, for my present invention relates particularly to these elements.

The chamber 15 communicates directly with an elongated opening 18, the forward end of which carries a fine needle valve 19, the same being preferably secured at 20 onto the end of the pipe 21, which pipe

comprises the forward portion of the passage 18. The needle rod has its forward portion 22 gradually tapered and of a size to completely close the passage in the cap 19 when the needle rod is thrown into extreme forward position by the spring 17. By moving the needle rod back and forth the amount of opening of the needle valve can be accurately regulated.

10 The air chamber 11 in advance of the partition 11^a is closed by a cap 23 which is threaded at 24 onto a lug 25 which comprises the rear portion of the color passage 18. This cap is provided with a pair of 15 oppositely disposed air pipes 26 and 27, the inner ends 28 of which communicate directly with the air space 11 and the outer ends 29 of which are bent inward close to the needle valve 19, so that the air is discharged very close to the color discharge end of the needle valve. In order to insure a discharge of air as close as possible to the needle valve, I cut away the inner faces 30 of the ends of the air pipes so that the 20 air is discharged not only from the ends of said pipes, but also from their sides against the outer surface of the end of the needle valve.

A study particularly of Figs. 3 and 5 30 will show that the ends of the air pipes will deliver the greater portion of the air at a point 31 just in advance of the end of the needle valve. Also, inasmuch as the two jets of air come from the opposite sides of the needle valve at equal angles thereto, any distorting tendency of one jet of air tending to throw the color off to one side is neutralized by the other jet of air, so that a perfectly balanced jet results, and the 10 color is carried straight out from the needle valve, and along the tip 32 of the needle.

It will also be seen by a study of the air discharge pipes as related to the needle valve that the color will be carried out in 15 a rather flat spray having its flat portion lying in a plane substantially at right angles to that of the pipes 26 and 27. This being the case, the color will be delivered onto the paper in a rather flat fine jet, so 20 that the line in which it is deposited on the paper will more nearly resemble that which is obtained in the use of a fine hair brush of ordinary form than it is possible to obtain by the use of either of the air 25 deliveries which are shown and described in my previous above mentioned patents.

It will be understood that the air pipes 26 and 27 are secured to or form a part of the cap 23, so that, by unscrewing the latter 30 from the lug 25, the cap and air pipes are both removed. This is done without in any way disturbing the needle valve, and thus it is possible to replace the cap and pipes, should the latter become clogged with

particles of dust, or should it become desirable to substitute a cap having pipes of larger capacity. Of course, the capacity of the brush is to a certain extent determined by the ultimate capacity of the air pipes and their discharge openings, pipes 70 of one diameter being better adapted to certain classes of work than pipes of another diameter. By making the cap and the pipes removable in the manner herein illustrated and described, I have provided 75 a brush which may be adapted to different classes of work with a minimum amount of adjustment.

I claim:

1. In an air brush, the combination with 80 a mechanism provided in its forward portion with a color discharge orifice, and a needle for controlling the opening of the same, and further provided with a screw-threaded lug; and an air chamber surrounding the same, of a cap threaded onto the lug to inclose the air chamber, and provided with a pair of oppositely disposed air pipes having their discharge openings adjacent the color discharge orifice, substantially as 85 described.

2. In an air brush, the combination with 90 a mechanism provided in its forward portion with a color discharge orifice, and further provided with a screw-threaded lug and 95 an air chamber surrounding the same, of a cap threaded onto the lug to inclose the air chamber and provided with a pair of oppositely disposed air pipes having their discharge openings adjacent the color discharge 100 orifice, substantially as described.

3. In an air brush, the combination of a 105 tubular shell, a partition within the same and located at a point inwardly from one end of the same, a color discharge tube outwardly projecting from the partition, an inclosing cap surrounding the color discharge tube and in contact with the end of the tubular shell, and a pair of air discharge tubes outwardly projecting from the cap on 110 opposite sides of the color discharge orifice, and terminating at a point adjacent to the color discharge orifice, substantially as described.

4. In an air brush, the combination of a 115 tubular shell, a partition within the same and located inwardly from one end of the same, a color discharge tube outwardly extending from the partition, a lug on said tube, an inclosing cap threaded onto the lug, 120 and serving to inclose a space in front of the partition, and a pair of air discharge tubes outwardly projecting from the cap on opposite sides of the color discharge tube, 125 substantially as described.

5. In an air brush, the combination of a member provided with a color discharge orifice, and an elongated tapered needle lo-

cated within the orifice and projecting therefrom, means for actuating the needle in and out to control the opening of the orifice, and a pair of oppositely disposed air discharge tubes located immediately adjacent opposite sides of the orifice member, and terminating at points substantially in line with each

other and immediately behind the end of the orifice member, substantially as described.

OLAUS C. WOLD.
